CLAIM

I claim the ornamental design for a tongs, as shown and described.

DESCRIPTION

FIG. 1 is a perspective view of a tongs, showing the new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a front view thereof, with the 7-tooth portion removed for clarity.

FIG. 9 is a rear view thereof, with the 6-tooth portion removed for clarity.

FIG. 10 is a front view of an alternative embodiment of a tongs.

FIG. 11 is a rear view thereof.

FIG. 12 is a left side view thereof.

FIG. 13 is a right side view thereof.

FIG. 14 is a top view thereof.

FIG. 15 is a bottom view thereof.

FIG. 16 is a front view thereof, with the 7-tooth portion removed for clarity; and,

FIG. 17 is a rear view thereof, with the 6-tooth portion removed for clarity.

The broken lines in the drawings illustrate portions of the tongs and form no part of the claimed design.
